UNITED STATES PATENT OFFICE.

BENJAMIN F. DICKSON, OF WEBB CITY, MISSOURI.

KNOCKDOWN-CRATE.

1,284,070.

Specification of Letters Patent.

Patented Nov. 5, 1918.

Application filed May 4, 1918. Serial No. 232,549.

To all whom it may concern:

Be it known that I, BENJAMIN F. DICKSON, a citizen of the United States, residing at Webb City, in the county of Jasper and State of Missouri, have invented new and useful Improvements in Knockdown Crates, of which the following is a specification.

This invention relates to shipping crates and aims to provide a crate of the knock-down type, which is simple and durable of construction and which may be quickly set up for use and when knocked down may be packed in a small space for storage or shipment.

To this end the invention includes a base, having separable sides, end and top walls, which may be secured to the base by a novel form of bracket located at each corner of the latter, this bracket including a standard having right angularly disposed wings adapted to overlap the side and end walls, said wings having laterally projecting studs adapted to enter the aligned openings in each of the side and end walls, to hold said walls against outward or upward movement with respect to the base, while a partition removably positioned between the side walls serves to prevent the walls from falling inwardly and dividing the crate into separate compartments.

In the drawings:

Figure 1 is a perspective view of a crate embodying the present invention and shown set up for use;

Fig. 2 is a central vertical longitudinal section of the same;

Fig. 3 is a horizontal section showing the engagement of the corner brackets with the side and end walls;

Fig. 4 is a detail perspective view of the bottom or base of the crate with the corner brackets in position ready to receive the side and end walls;

Fig. 5 is a detail perspective view of one of the end walls;

Fig. 6 is a detail sectional view showing the manner of connecting the corner brackets with the base of the crate; and

Fig. 7 is a detail perspective view of one of the corner brackets.

Referring to the drawings in detail, where-in like characters of reference denote corresponding parts, the crate includes a bottom wall or base 10, which is herein shown as

rectangular in plan. The crate also includes side walls 11, end walls 12 and a top wall or closure 13, all of the said walls being separately formed and removably joined together in a manner hereinafter apparent.

Secured to each corner of the base 10 is a novel form of bracket, which is adapted to engage both the side walls and end walls and when the said walls are in assembled position to hold them against outward movement. These brackets include a standard 14, which is preferably but not necessarily rectangular in cross section and is provided at its lower end with a cylindrical threaded extension 15, which is adapted to enter an opening 16 provided in each of the corners of the base 10. The juncture of the squared portion of the standard 14 and the threaded portion 15 provides a shoulder 17 which is adapted to bear upon a washer 18 positioned upon the shank and engageable with the upper surface of the base 10. The threaded extension 15 of the standard projects beyond the opposite face of the base for the reception of a bar 19 provided adjacent each of its ends with an opening 20 which receives the said extension. The bar 19 is disposed transversely beneath the base and engages the adjacent threaded extensions of the standards 14 and the said extensions have positioned thereon clamping nuts 21 which serve to hold the brackets in position. Carried by the upper and opposite end of the standard 14 are right angularly disposed wings 22, arranged transversely of the said standard for engagement with the side walls and end walls of the crate. These wings have projecting laterally and inwardly studs 23, for engagement with openings 24 and 25 provided in the side and end walls respectively.

The end walls are cut away at their opposite lower edges as shown at 26 to receive the standards 14 and the side walls 11 are positioned between the end walls. When so arranged the corner brackets will effectually hold the end walls against outward movement while the said walls 11 will prevent any inward movement of the end walls.

Positioned transversely of the crate upon the interior thereof is a partition 27, which is adapted to engage grooves 28 and 29 formed respectively in the base 10 and side walls 11. This will prevent inward move-

ment of the side walls while the brackets will prevent movement of the said walls in an opposite direction.

The crate is designed to be closed by a cover 13, which carries at each end transversely disposed cleats 30 engageable along the upper edges of each of the end walls 12. The crate is also provided upon opposite sides with pivoted hooks 30, which are adapted to engage eyes 31 located upon the outer surfaces of the side walls 11. If desired straps 32 may be secured around the crate both longitudinally and transversely, these straps being especially useful to prevent the separation and accidental loss of the parts when the crate is in a knockdown position.

The invention is susceptible of various changes in its form, proportions and minor details of construction and the right is reserved to make such changes.

Having described the invention, what is claimed is:—

1. A crate comprising a base, separate end walls, separate side walls fitting between the end walls to hold the latter spaced apart, a transverse partition engageable with the side walls to prevent inward movement of the latter, standards removably secured to each corner of the base and rising therefrom,

right angularly disposed wings carried by the standards and means for removably securing the wings to the side and end walls.

2. A crate comprising a base, separate end walls, separate side walls fitting between the end walls to hold the latter spaced apart, a transverse partition engageable with the side walls to prevent inward movement of the latter, standards removably secured to each corner of the base and rising therefrom, right angularly disposed wings carried by the standards and laterally and inwardly projecting studs carried by the wings for engagement in openings formed in the side and end walls to hold the latter against outward and upward movement with respect to the base.

3. In a crate, the combination with a base having removable side and end walls, of brackets secured to each of the corners of the base, each of said brackets comprising an elongated member, means located at one end of said member for engagement with the base, right angularly disposed side wings arranged transversely of said member and means carried by each of said wings for engagement with the side and end walls.

In testimony whereof I affix my signature.

BENJAMIN F. DICKSON.
